ATTORNEY

UNITED STATES PATENT OFFICE.

JOHN L. SANFACON, OF INKSTER, NORTH DAKOTA.

CROSSING INDICATOR.

Application filed July 24, 1922. Serial No. 577,185.

To all whom it may concern:

Be it known that I, JOHN L. SANFACON, a citizen of the United States, residing at Inkster, in the county of Grand Forks and 5 State of North Dakota, have invented new and useful Improvements in Crossing Indicators, of which the following is a specification.

The object of this invention is to provide 10 means for indicating a danger point in the road ahead so as to warn vehicle drivers of said danger point in time for them to check their speed before they reach said point.

Another object of the invention is to make 15 the device movable so that it will swing out of the way when struck by a loaded vehicle of great height.

A still further object of the invention is to provide streamers on the device to attract 20 attention thereto.

This invention also consists in certain other features of construction and in the combination and arrangement of the several parts, to be hereinafter fully described, illustrated in the accompanying drawings and 25 specifically pointed out in the appended claim.

In describing my invention in detail, reference will be had to the accompanying 30 drawings wherein like characters denote like or corresponding parts throughout the several views, and in which:—

Figure 1 is a view showing a portion of a road with my invention in place.

Figure 2 is a plan view of Figure 1.

Figure 3 is a section on line 3—3 of Figure 1.

Figure 4 is a section on line 4—4 of Figure 1.

Figure 5 is a section on line 5—5 of Figure 4.

Figure 6 is a section on line 6—6 of Figure 5.

Heretofore danger signs have been placed 45 alongside the road but as most drivers keep their eyes on the road ahead it often happens that such signs are ignored by not being seen and thus the driver strikes the danger point without warning.

It is the object of my invention to so place 50 the sign that the driver cannot help but see it and I also place streamers on the sign to attract the driver's attention thereto. In carrying out my invention I place a post 1

alongside the road and place a frame 2 at 55 the top of the post, the major portion of which projects out over the road. This frame carries a sign 3 which may be of any suitable construction and which may contain any warning symbols. The frame is 60 pivotally connected with the post, as shown at 4, and springs 5, connected with the rear end of the frame and with an arm 6 on the post, tend to hold the frame in a position at right angles to the road. Streamers 7 are 65 suitably connected with the lower edge of the frame and extend downwardly over the road. The frame may be provided with clips for containing small signs containing advertisement, as shown at 9. The post is 70 supported by the braces 10, one of which contains a spring 11 and I also may provide a brace rod 12 for the post.

The symbols may be placed on the sign by 75 luminous paint or the device may be illuminated by a lamp or the like.

As will be seen from Figures 1 and 2 the sign extends out over the road and is located at a sufficient height to permit vehicles to pass under the same. If a vehicle with a tall 80 load should pass along the road, such as a load of hay, and strike the sign, the frame would simply swing on its pivot to permit the vehicle to pass and then the springs 85 would bring the frame back to normal position.

As will be seen a driver with his eyes on the road ahead cannot help but see the sign as it is in his line of vision and the streamers suspended on the frame will attract his attention to the same. Thus the driver will be warned and it is impossible for him to go by the sign without seeing it.

The device may be provided with means for indicating the route and it may also be 90 provided with a flag holder and with projections for enabling a person to climb up the same.

It is thought from the foregoing description that the advantages and novel features 100 of my invention will be readily apparent.

I desire it to be understood that I may make changes in the construction and in the combination and arrangement of the several parts, provided that such changes fall within the scope of the appended claims.

What I claim is:—

A sign of the class described comprising

a post placed alongside a road, a frame pivotally secured to the top of the post and extending out over the road with its rear part extending beyond the post, an arm carried by the post, a pair of springs, each having one end connected with one end of the arm and its other end with the rear of the

frame, said springs holding the frame at right angles to the road, a symbol carrying member in the frame and streamers attached to the under edge of the frame.

In testimony whereof I affix my signature.

JOHN L. SANFACON.
